CLAIM

The ornamental design for a tray for orthopedic screws, as shown in the drawings.

DESCRIPTION

FIG. 1 is a front top right perspective view of a tray for orthopedic screws showing my new design;

FIG. 2 is a rear top left perspective view thereof;

FIG. 3 is a rear bottom right perspective view thereof;

FIG. 4 is a front elevation view thereof;

FIG. 5 is a rear view thereof;

FIG. 6 is a top plan view thereof;

FIG. 7 is a bottom plan view thereof;

FIG. 8 is a left side elevation view thereof; and,

FIG. 9 is a right side elevation view thereof.

The broken lines depict portions of the tray for orthopedic screws that form no part of the claimed design.
